UNITED STATES PATENT OFFICE.

RICHARD A. BRACE, OF FULTONVILLE, NEW YORK, ASSIGNOR TO WHITE MOP WRINGER COMPANY, OF FULTONVILLE, NEW YORK, A CORPORATION OF NEW YORK.

MOP-WRINGER.

1,268,921.

Specification of Letters Patent. Patented June 11, 1918.

Application filed November 9, 1917. Serial No. 201,020.

To all whom it may concern:

Be it known that I, RICHARD A. BRACE, citizen of the United States, residing at Fultonville, county of Montgomery, State 5 of New York, have invented a certain new and useful Improvement in Mop-Wringers, and declare the following to be a full, clear, and exact description of the same, such as will enable others skilled in the art to which 10 it pertains to make and use the same, reference being had to the accompanying drawings, which form a part of this specification.

My invention relates to mop wringers shown in the accompanying drawings and 15 more particularly described in the following specification and claims.

One of the objects of this invention is an improvement in the general construction and operation of the mop wringer on which 20 U. S. Patent No. 976,238 was granted to Hubert C. White on 22nd day of November, 1910.

Another purpose of this invention is to reduce the cost of manufacture without di- 25 minishing the efficiency of the invention.

Another object of the invention is to pro- 30 vide means for guiding the lower edge of the mop upon being placed between the presser boards that it may not become en- tangled between the lower edge of the 35 presser board and the bottom board upon actuating the movable presser board.

By referring to the drawings in the White 40 patent it will be seen that the arms of the rock shaft,—to which the toggle mechanism for operating the presser board is pivotally connected,—are in radial alinement with the arm at the end of the rock shaft to which the operating lever is bolted. It will therefore be obvious that in order to drill the 45 hole in each of the rocker arms to receive the pivot for the respective toggle mechanism connected therewith, a drill must be provided of sufficient length to reach from the rocker arm to rocker arm, as the holes can only be drilled from one end of the shaft because of the operating lever arm at the opposite end of the shaft being in radial alinement with said rocker arms. It has therefore required a relatively long drill 50 to perform this operation which frequently breaks, greatly adding to the cost of production. It has also been found in actual practice that greater care must be exercised

and more time consumed than is now re- 55 quired to manufacture this part of the wringer.

One of the objects, therefore, of this invention is to overcome these objections and thereby reduce the cost of manufacture by 60 forming the arm at the end of the rock shaft to which the operating lever is se- cured with a sufficient offset to admit of 65 drilling a hole in the rocker arm from the end of the shaft nearest the respective arm,— thus a shorter drill may be employed with less liability of breakage and with greater 70 production for a given period.

Another feature of the invention consists 75 in constructing the bell crank lever of the toggle mechanism with projecting lugs to serve in place of the loose pivot pins for- 80 merly employed. The lugs on the bell crank, which is preferably made of malleable iron, may thus be burred when the parts are as- 85 sembled to prevent accidental disengagement. This also cheapens the cost of manu- 90 facture.

With the foregoing and other objects in 95 view which will appear as the description proceeds, the invention resides in the combination and arrangement of parts and in the details of construction hereinafter described and claimed, it being understood that changes may be made in the precise embodiment herein disclosed without departing 100 from the spirit of the invention.

In the accompanying drawings, Figure 1 is a perspective view of the mop wringer 105 as it would appear supported on the rim of a pail,—indicated in dotted lines.

Fig. 2 is a vertical cross-sectional view on line 2—2 of Fig. 1 looking in the direction of the arrows.

Fig. 3 is a perspective view of the rock 110 shaft and the bell crank toggle mechanism.

Referring now to the letters of reference placed upon the drawings:

A, A, are side frames or brackets pro- 115 vided with hooked portions A', adapted to straddle the rim of a pail B. The side frames A, A, are provided with channels in which are lodged the edges of the fixed presser plate or board C, secured thereto by suitable bolts. The lower edge of the 120 plate C, is provided with a projecting lip or flange C', to direct and guide the lower or 125 free end of the mop when inserted in the

device away from the presser board, as will be hereafter more fully explained. C², is a stiffening rib extending transversely across the back of the plate C, to strengthen an otherwise relatively light plate. C³, is a flange at the top of the plate which in conjunction with the flange C' also serves to stiffen the plate.

Pivoted to the depending legs A², of the side frames are swinging members D, formed with a channel, to receive the ends of the presser board E, which is preferably formed of wood.

F, are springs between the depending legs A², and the swinging members D, serving to force the presser boards apart in position to receive the mop between them.

G, indicates a rock shaft supported by the side frames A, A.

20 Adjacent to each end of the rocker shaft is a rocker arm G', integral therewith. Pivotedly connected with each rocker arm is a link H, in turn respectively pivoted to a bell crank arm I. The opposite end of the bell crank arms I, are pivotally connected with the swinging members D, by lugs I', integral with the bell crank arms and which may be burred when the parts are assembled to insure against displacement.

30 At the end of the rock shaft is an arm G², integral therewith to which is bolted an operating lever G³. In the present construction the arm G², is offset from radial alinement with the rocker arms G', in order 35 that the holes provided in the latter to receive the pivots of the connecting links H, may be drilled from each end of the rock shaft without interference with the arm G².

40 J, is a bottom board secured to a projecting arm of the swinging member extending beneath the projecting lip C', of the presser plate C.

Having indicated the several parts by reference letters, the construction and operation of the device will be readily understood. Upon inserting a mop between the presser boards the projecting lip C', at the lower edge of the presser board C, serves to direct the free end of the mop away from 50 the fixed presser board that the mop may not become entangled between the edge of the bottom board and the presser board when operating the lever G³.

The operation of the lever G³, serves to 55 force the presser boards together, thereby forcing the water out of the mop through the perforations in the presser board and

between the bottom board and presser board into the pail.

As previously indicated, by constructing 60 the arm of the rock shaft to which the operating lever is bolted with an offset that it may be out of radial alinement with the rocker arms the pivot holes in the latter may be drilled from the end of the shaft 65 adjacent to the respective rocker arm, thereby permitting the use of a relatively short drill and reducing the cost due to breakage and time required to perform the operation. So also the rivets connecting the rocker arm 70 adjacent to the operating lever may be rivet headed with a riveting machine instead of by hand as required under the construction shown in the White wringer referred to in the opening paragraph of this specification. 75

Having thus described my invention, what I claim is—

1. In a mop wringer, side frames provided with means to engage the wall of a pail, a presser board carried by the side frames, 80 swinging members pivoted to the frames carrying a presser board, a shaft journaled in the frame having rocker arms spaced apart and also from the ends of the shaft with a hole in each arm in axial alinement to receive the pin of a toggle lever mechanism, and with an operating arm at one end of the shaft offset from radial alinement with the rocker arms and also laterally therefrom, whereby the pivot holes in the latter may 85 be drilled from each end of the shaft, and toggle lever mechanism pivoted to said rocker arms and to said swinging members.

2. In a mop wringer, a frame having a presser plate, swinging members pivoted to 90 the frame and provided with a presser board, a shaft journaled in the frame and provided at points spaced from its ends with spaced rocker arms having holes at their outer portions, an operating arm located at 100 one end of the shaft in spaced relation with the adjacent rocker arm and also spaced laterally therefrom to permit the said holes in the rocker arms to be drilled from each end of the shaft, and means for connecting 105 the swinging members with the rocker arms having pivots arranged in the holes of the latter.

In testimony whereof, I sign this specification in the presence of two witnesses.

RICHARD A. BRACE.
